UNITED STATES PATENT OFFICE.

GLENN W. PACKER, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIAL.

Application filed December 16, 1920, Serial No. 431,251. Renewed April 10, 1925.

To all whom it may concern:

Be it known that I, GLENN W. PACKER, a citizen of the United States, residing at Chicago, in the county of Cook and State of Illinois, have invented an Apparatus for Handling Loose Material, of which the following is a specification.

This invention relates to improvements in apparatus for handling loose material and more particularly to scraping devices for transporting coal from the working face of a mine to an entry for loading in mine cars. The object of the present invention is to provide a simple and more efficient apparatus of the class above described and an improved method of operating the same.

My invention may best be understood by reference to the accompanying drawings, in which,

20 Figure 1 is a top plan view of the turning mechanism, comprising part of my improved apparatus.

Figures 2 to 5 inclusive, are diagrammatic views illustrating a typical installation of the apparatus in a mine, and showing the scraper in various positions with respect to the turning mechanism.

Figure 6 is a vertical cross section of the turning mechanism, taken on line 6-6 of Figure 1.

Figure 7 is a detail.

Scrapers loading devices which have heretofore been used in mines usually include a scraper which is moved by means of flexible cable operated by a suitable hoisting engine. With devices of this character, however, it is often found necessary, on account of operating conditions, to change the direction of movement of the scraper in moving it from the working face to the point of loading on the cars, and again in returning to the starting point. For instance, when such a device is used in the room and pillar system of mining, the working face of the mine is usually at an angle to the direction of movement of the scraper toward the room entrance. As a large portion of the room is usually occupied with waste material or mine props, it is necessary to direct the scraper first along the mine face and then in a path along one side of the room toward the room entrance. Heretofore the forward movement of the scraper has been changed by providing one or more fixed sheaves adjacent the end of the working face

and adapted to be detachably engaged by the head rope or drag line of the scraper. The return or rearward movement of the scraper has been directed by a deflector or guide pulley positioned near the point at which the scraper is turned in its forward movement.

In the drawings, the present invention is shown as applied to a typical mining operation of the room and pillar system, and comprises a scoop or scraper 1 having a head rope 2 and a tail rope 3, each of said ropes being operated by a suitable hoisting engine, (not shown) usually situated at or outside of the entrance of the mine room. A preferred construction of the scraper 1 comprises a body portion including upright side walls 1^A, 1^A converging at the rear of the scraper in a rounded end portion 1^B.

The working face 5 of the room is advanced longitudinally of the room as the mining operation proceeds. In the room illustrated, this face is formed substantially at right angles to the side walls 6 and 7, although it may be found preferable under some circumstances to form the face at an obtuse angle to the side wall 7 nearest the room entrance, as will subsequently appear. The tail rope 3 is led around a stationary sheave 8 anchored in the far corner of the room and from thence around suitable guiding sheaves to the hoisting engine. At the opposite corner of the room, but removed somewhat from the working face and wall 7, I provide a turning device 9 which comprises a pair of arms 10, 11, at angles to each other and mounted to swing substantially in a horizontal plane about a pivot 12. The arm 10 is preferably longer than the arm 11. A preferred means of securing said turning device in place comprises a screw jack 13, having a spiked upper end adapted to engage the mine roof in the usual manner, and an irregularly shaped retaining member 14 at its lower end adapted to engage a base plate 15. Said retaining member is preferably formed in the shape of an inverted prism having the lower edge 16 thereof inserted in a slot 17 in said base plate as shown. The base plate is provided with suitable downwardly extending portions for engaging the floor of the mine, preferably formed by turning the corners 15^A, 15^B, of said base plate downwardly as shown. Suitable stops 18, 19, herein shown as attached to the base plate 15 for limiting the movement

of the turning device 9 as will hereinafter appear. The stops 18 and 19 obviously may be provided independently of the base plate, if desired; for example, separate jacks may 5 be suitably positioned for this purpose. A pair of vertically disposed flanged rollers 20, 21, are mounted one on each end of the arms 10, 11, respectively. When in operation, and jack 13 is placed in a vertical position and forms a pivot bearing for the turning device 9 as shown.

10 The use and operation of my device is as follows:

When the scraper is in starting position 15 shown in full lines in Figure 2, the lead rope 2 is engaged about the pulley 20 on the end of arm 10. When a pulling force is exerted on the lead rope, the turning device 10 is restrained from rotation by the stop 18 on the base plate 15. From the initial position, the scraper along the mine face 5, gathers a load of coal, and approaches the turning device 9 until the scraper is brought into contact with the arm 10 as 20 shown in dotted lines in Figure 2. A continued pull on the head rope 2 will swing the turning device about its pivot, causing the scraper to turn therewith. As the arm 11 turns with the arm 10, the roller 21 of 25 the former is swung into position shown in Figure 3, where it will contact with the tail rope 3 after the scraper is advanced in the changed direction. The turning device continues to pivot until the arm 10 30 engages the stop 19 on the base plate 15 as shown in Figure 4, in which position the scraper is fully turned into line with the entrance of the room, the tail rope 3 is engaged by the roller 21, and the scraper may 35 continue its movement toward the room entrance to be unloaded in the usual manner.

40 The returning movement of the scraper to the starting point is substantially the reverse of the above described movements, viz, the head rope 2 is released, and the tail rope 3 is pulled so as to bring the rear end of the scraper into engagement with the arm 11 to pivot the turning device in the reverse direction. The roller 10 is brought 45 into contact with the head rope 2 and the scraper is returned to a position substantially parallel with the working face 5, as shown in dotted lines in Figure 5, from whence it may be drawn rearwardly to the 50 starting position in the far corner of the room.

55 In the preferred form of my device illustrated, the arm 10 is somewhat longer than the arm 11, so that the scraper will be swung in a path nearer the working face 5 during its forward or loading movement than when the scraper is being returned to its starting position, as will be seen by comparing Figures 2 and 5. It will further be noted that the arms 10 and 11 are positioned

at an oblique angle to each other. This arrangement is preferable in cases where the change of direction of movement of the scraper loader is approximately at a right angle, but would not be necessary in cases 70 where the change in direction is more than a right angle.

75 It has been before suggested that the working face 5 might be formed at an obtuse angle to the side wall 7. Such an arrangement has been found to be more economical in many cases where mining conditions permit, on account of the increased length of the working face afforded by this 80 arrangement.

85 From the above description, it will be seen that as the working face 5 is advanced, the fixed sheave 8 and the turning device 9 will be advanced accordingly, to transport the coal away from the face. The apparatus is easily put in place, and affords a continuous movement of the scraper both forwardly and backwardly about the turning device, and minimizes the manual labor required for handling the draft ropes 90 and scraper.

95 It will be understood that I have shown my improved apparatus as applied to one system of mining merely for the purpose of illustration of its use, but that it is readily adapted to diversified uses for transporting material, as for instance in excavating and grading operations. Furthermore, I do not wish to be understood as 100 limiting myself to the construction of apparatus illustrated excepting as specifically defined in the appended claims.

105 I claim as my invention:

1. In a device of the class described, in combination with a scraper, two draft devices for moving the same in opposite directions, and a turning device adapted to be moved by said scraper into a plurality of positions for successively engaging said draft devices. 110

115 2. In a device of the class described, in combination with a scraper, two draft devices for moving the same in opposite directions, a turning device adapted to be moved by said scraper into a plurality of positions for successively engaging said draft devices and means for limiting the movement of said turning device.

120 3. In a conveying apparatus, in combination with a scraper having two draft devices for moving the same in opposite directions, a turning device having a pair of operatively connected bearing members spaced apart, for successively engaging said draft devices. 125

130 4. In a conveying apparatus, in combination with a scraper having two draft devices for moving the same in opposite directions, a turning device having a pair of operatively connected bearing members spaced

apart, for successively engaging said draft devices, and means for limiting the movement of said bearing members.

5. In a conveying apparatus, in combination with a scraper, having suitable draft devices, a turning device comprising two rocking arms arranged at an angle to each other and each adapted to successively engage the draft devices at either end of said scraper.

6. In a conveying apparatus, in combination with a scraper, having suitable draft devices, a turning device comprising two rocking arms arranged at an angle to each other and each adapted to successively engage the draft devices at either end of said scraper, and means for limiting the movement of said arms.

7. In a conveying apparatus, in combination with a scraper having suitable draft devices, a turning device comprising two rocking arms arranged at an angle to each other, each adapted to successively engage the draft devices at either end of said scraper, said arms being of different lengths.

8. In a conveying apparatus, in combination with a scraper having suitable draft devices, a turning device comprising two rocking arms of different lengths arranged at an angle to each other and each adapted to successively engage the draft devices at either end of said scraper, and means for limiting the movement of said arms.

9. In a conveying apparatus, in combination with a scraper having suitable draft devices, a turning device comprising two rocking arms provided with bearing members for said draft devices, one of said arms coacting with the scraper to move the other arm into engagement with the sides of said scraper adjacent to the rear end thereof.

10. In a conveying apparatus, in combination with a scraper having suitable draft devices, a turning device comprising two rocking arms provided with bearing members for said draft devices, one of said arms coacting with the advance end of the scraper to move the other arm into engagement with the side of such scraper, adjacent to the rear end thereof, and means for limiting the movement of one of said arms.

11. In combination with a draft operated scraper, a turning device, means for mounting said device comprising a bearing member having an irregularly shaped projection at its lower end, a base plate having a corresponding depression for receiving said pro-

jection, and means for applying pressure on said bearing member.

12. In combination with a draft operated scraper, a turning device, means for mounting said device comprising a bearing member, a separable base plate for engaging the floor, and means on said base plate for limiting the movement of said turning device.

13. In combination with a draft operated scraper, a turning device, means for mounting said device comprising a bearing member having an irregularly shaped projection at its lower end, a base plate having a corresponding depression for receiving said projection, means for applying pressure on said bearing member, and means on said base plate for limiting the movement of said turning device.

14. In a conveying apparatus, a scraper having side walls converging toward the rear end thereof, draft devices for moving the scraper in opposite directions, a turning device having a pair of operatively connected bearing members spaced apart, for successively engaging said draft devices.

15. In a conveying apparatus, a scraper having side walls converging toward the rear end thereof, draft devices for moving the scraper in opposite directions, a turning device comprising two rocking arms arranged at an angle to each other and each adapted to successively engage the draft devices at either end of said scraper.

16. In a conveying apparatus, a scraper having side walls converging toward the rear end thereof, draft devices for moving the scraper in opposite directions, a turning device comprising two rocking arms provided with bearing members for said draft devices, one of said arms coacting with the scraper to move the other arm into engagement with the side of said scraper adjacent to the rear end thereof.

17. In the conveying apparatus, a scraper having side walls converging towards the rear end thereof, draft devices for moving the scraper in opposite directions, a turning device comprising two rocking arms provided with bearing members for said draft devices, one of said arms coacting with the scraper to move the other arm into engagement with the side of said scraper adjacent to the rear end thereof, and means for limiting the movement of said turning device.

Signed at Chicago, Illinois, this 13 day of December 1920.

GLENN W. PACKER.
